UNITED STATES PATENT OFFICE.

FRANK THIEL, OF ST. JOHN, INDIANA.

MEANS AND METHOD FOR BUILDING SILOS.

1,370,166.

Specification of Letters Patent.

Patented Mar. 1, 1921.

Application filed February 16, 1920. Serial No. 359,051.

To all whom it may concern:

Be it known that I, FRANK THIEL, a citizen of the United States, and a resident of St. John, in the county of Lake and State of Indiana, have invented a new and useful Improvement in Means and Methods for Building Silos, of which the following is a full, clear, and exact description.

My invention relates to improvements in means and methods for building silos, and it consists in the combinations, constructions and arrangements herein described and claimed, and in the steps hereinafter set forth.

An object of my invention is to provide means for building silos, by the use of which the expense of erecting the ordinary scaffolding of lumber is obviated, as well as the work and expense of again removing the scaffolding when the silo is finished.

A further object of my invention is to provide a means for erecting silos which comprise a series of portable hangers or scaffold units that are raised as the structure is progressively built up and which form supports for workmen and material.

A further object of my invention is to provide means for building silos which, when the silo is built, may be lowered and used over and over again under similar circumstances.

A further object of my invention is to provide a process, by means of which the expense in building silos is materially reduced and in which the labor is cut down to a minimum.

Other objects and advantages will appear in the following specification, and the novel features of the invention will be particularly pointed out in the appended claims.

My invention is illustrated in the accompanying drawings, forming part of this application, in which—

Figure 1 is a top plan view of the silo and scaffold,

Fig. 2 is a side view of the top portion of the silo showing one scaffold,

Fig. 3 is a side view of the top portion of the silo showing two scaffolds, and

Fig. 4 is a perspective view of one of the units of the scaffold.

The present invention is designed to facilitate the building of silos of the type in which there is a circular wall of strips 3 which are disposed vertically. These strips are made preferably in 10 foot lengths, but

adjacent strips are lapped for a distance of 5 feet. In other words, a circular row of vertical strips is formed by alternating boards, while the next higher row is composed of intermediate boards having their upper ends disposed on the line substantially 5 feet above the upper ends of the adjacent lower row.

In Fig. 2 I have shown a silo partly completed, the upper ends of the top row being in alignment and the upper ends of the next lower row terminating short of the first named row, thereby forming spaces 3^a between the boards 3. After a row of boards 70 is added, the wall 2 is built up a corresponding distance.

When the building of the silo has progressed so far that the builders cannot reach high enough to work, a portable scaffold is provided upon which the builders may continue to build the silo. This scaffold consists of four similar removable hanger units placed across the top of the partly completed silo and boards laid across the ends 80 of the units to form a platform.

Each unit consists of a main supporting member 4 having bolted to it at each end two short members 5 and 6 to which is bolted a connecting member 7. The members 5, 6 85 and 7 form a socket for foot boards, as explained later, the member 7 being the supporting member, and the members 5 and 6 preventing the dislodgment of the foot board by lateral movement. Two of these 90 units are laid parallel to each other across the top of the partly completed silo, and the other two are laid across the silo at right angles to the first two (see Fig. 1). The members 4 of the units rest on the tops of 95 the next to the last row of boards 3 and between the extending halves of the last row of boards 3 (see Fig. 2). Foot boards 8 are placed from the ends of one unit to the other. This forms a platform around 100 the outside of the silo on which the builders can work.

Let us assume that the silo has been built up far enough for the first portable scaffold to be put up. First the four similar hanger 105 units are laid across the partly completed silo as stated above. Then the boards 8 are placed around the silo on the members 7 (see Fig. 2). This forms a platform by means of which the tile wall is built. Material is hoisted on the platform and the tile wall is built up to the level of the mem-

bers 4. The boards 8 are then placed on the extensions of the members 4 as indicated in dotted lines in Fig. 2. This forms a platform on which the wall 1 is built up. Material is hoisted on the platform and a row of boards 3 is added to the wall 1. In the spaces where the members 4 are placed, the boards 3 are left out until after the scaffold has been removed.

- 10 To proceed with the building of the silo, a second portable scaffold is used. The second scaffold is similar to the scaffold described. The four units of the second scaffold are placed in position on the silo (see 15 Figs. 1 and 3) a step higher than the first scaffold, which is equal to one-half of the length of the boards 3. The boards 8 are then placed on the ends of the members 4 of the second or upper scaffold, as shown in 20 Fig. 3. The four units of the lower scaffold are now ready to be removed.

To remove the hanger units of the lower scaffold, the builders let down a rope with a hook attached to it, and lift one unit out 25 at a time through the space between the boards 3. The units of the lower scaffold are then placed on the retaining bolts 9, as shown in dotted lines in Fig. 3, the bolts 9 being secured to the members 6.

- 30 After the lower hanger units have been disposed on the bolts 9, the boards 3 are driven in the spaces in which the members 4 of the units were placed. The boards 8 are then taken from the ends of the members 35 4 and placed on the members 7. Material is again hoisted and the builders build the tile wall up to the level of the members 4. The boards 8 are then positioned on the ends of the members 4. Material is hoisted 40 on the platform formed by the boards 8 on the ends of the members 4, and another row of the boards 3 is added to the wall 1. The boards 3, for the spaces in which are positioned the members 4, are driven in after 45 the members 4 are removed.

The scaffold is now not high enough to proceed with the building of the silo. The hanger units of the scaffold, which are hanging on the retaining bolts 9, are lifted 50 up and placed in position across the silo one step higher than the scaffold on which the builders are working. The same method for

constructing the remainder of the silo is used as described above.

I claim:

1. In a scaffold for constructing silos, a hanger unit, comprising a supporting strip adapted to extend across the silo and beyond the opposite sides thereof, and a depending foot board holding socket at each end of the strip.

2. In a scaffold for constructing silos, a pair of hanger units disposed in substantially parallel relation, each of said units providing a supporting strip adapted to extend across the silo and beyond the opposite sides thereof, and having depending foot board holding sockets at the ends of the strips, a similar pair of hanger units disposed substantially at right angles to the first named pair, and foot boards extending between adjacent sockets.

3. In a scaffold for constructing silos, having walls of vertically disposed strips, the adjacent strips being lapped, a pair of hanger units disposed in substantially parallel relation and arranged to rest on the ends of certain of said strips, a second pair of hanger units disposed substantially at right angles to the first named pair and arranged to rest on the ends of strips in substantially the same plane with the first named hangers, each of said supporting strips being provided with a foot board holding socket depending therefrom outside of the walls of the silo, and foot boards disposed between adjacent sockets.

4. The herein described steps in the process of building silos, having walls consisting of vertically disposed strips, the adjacent strips being lapped, which consists in supporting a scaffold on the tops of the aligned ends of certain of said strips, placing intermediate lapping strips in position, placing a second scaffold on the tops of the aligned ends of the lapping intermediate strips, removing the first mentioned scaffold and placing it on the aligned tops of the strips on the next higher plane above the ends of the strips on which the second scaffold rests, and progressively inserting strips and raising the scaffold alternately.

FRANK THIEL.
